UNITED STATES PATENT OFFICE.

JOSEPH P. GLASER, OF DETROIT, MICHIGAN, ASSIGNOR TO CHAMBERLIN METAL WEATHER STRIP COMPANY, OF DETROIT, MICHIGAN.

WEATHER-STRIP.

1,379,912.

Specification of Letters Patent. Patented May 31, 1921.

Application filed September 27, 1917. Serial No. 193,523.

To all whom it may concern:

Be it known that I, JOSEPH P. GLASER, citizen of the United States, residing at 109 Third Ave., Detroit, in the county of 5 Wayne and State of Michigan, have invented certain new and useful Improvements in Weather-Strips, of which the following is a specification, reference being had therein to the accompanying drawing.

10 This invention relates to improvements in weather strips of the class particularly adapted for casement windows and the like to provide a seal against the entrance of moisture, air, dust, etc., between the sill of 15 the frame or casing and the bottom of the swinging member or sash.

The object of the invention is to provide a simple, light, cheap construction of this nature that will be strong and durable in 20 use and will afford an efficient weather proof fitting or joint.

The invention will be understood from the hereinafter contained detail description when considered in connection with the accompanying drawings forming part hereof and illustrating one embodiment of the invention.

In the drawings:

Figure 1 is a vertical section of a casement window equipped with a weather strip constructed in accordance with the present invention; and

Fig. 2 is a detail perspective view of one of the strip elements or members.

35 In the drawings, I have illustrated, by way of example, a preferred embodiment of the invention. In this connection it will be understood that variations and minor changes in the particular construction 40 shown, as will appeal to those skilled in the art and falling within the scope of the appended claims may be made without departing from the spirit of the invention. The special construction shown in the drawing 45 comprises two coöperating metal strip elements A—B, shown in the present instance as applied respectively to the bottom rail of the swinging member A' and to the sill of the frame or casing B'. Both of the strip 50 elements or members A—B are preferably formed from flexible sheet metal, such as sheet zinc, copper or the like.

The strip element A has a portion or flange a to fit against the under face of the 55 sash rail, and at one side thereof a roll or

pocket like portion a' open at one side. The strip member A is formed by curling one side portion of the strip out away from the portion a and around and back, the pocket or roll portion having a general 60 semi-circular shape in cross section. The strip element A may be secured upon the face of the sash rail in any desired way. As shown, the strip element A is secured in place within the rabbet C of the sash rail 65 by a row of tacks or similar fastening members a² passing through the portion or flange a.

The sill strip B is formed by doubling the strip upon itself intermediate its side 70 marginal portions to form an upstanding part or flange b and the outstanding side flanges b' b², the upstanding part or flange b being bent outwardly and up in a curve, and thence back to provide the outwardly extending roll or partially tubular portion b³ open at one side, the exterior of 75 said partially tubular or roll portion being of a size and shape corresponding to the pocket or roll portion a' of the strip member 80 A to fit tightly therein. The strip member B is secured upon the upper face of the sill in any desired manner, for instance, as shown by a row of tacks or like fastening members b⁵ passing through the outstanding side flanges b' b².

When the window sash or swinging member is in closed position, as shown in Fig. 1 of the drawings, the flexible roll portion b³ of the member B fits tightly within the 90 flexible pocket or roll portion a' of the sash strip A, the outer face of the roll portion b³ being in close fitting engagement throughout with the inner wall of the pocket or roll portion a', a channel b⁴ being 95 provided at one side of the interfitting roll portions, and beneath the outer marginal edge of the roll portion b', said channel b⁴ serving to assist in preventing the entrance of moisture, air, dust, etc., between the roll 100 portions.

The weather strip hereinbefore described, it will be observed is extremely simple in construction and can be manufactured very cheaply from stock materials. The construction is of a durable nature and provides an efficient seal against the entrance of moisture, air, dust, etc., between the parts

What I claim is:

1. The combination with a casement win-

dow or the like including a swinging sash, and a window frame having a sill, of a weather strip comprising two coöperating strip elements secured upon the bottom rail 5 of the sash and the sill of the window frame respectively, one of said strip elements having a tubular part open at one side, and the other strip element being provided with an upstanding part having at its upper end a tubular portion extending laterally to one side thereof and open at one side, the last mentioned tubular portion being of a size and shape corresponding to the interior of the tubular part of the other strip element to fit 10 within the same with its outer face throughout in close contact with the inner face of the other tubular part throughout the same when the window sash is in closed position, the open side of the inner tubular portion of 15 one of the strips facing outwardly and providing a channel at one side of the interfitting tubular parts of the strips beneath the outer marginal edge of the inner tubular part.

20 2. The combination with a casement window or the like including a swinging sash, and a window frame having a sill, of a weather strip comprising two coöperating strip elements constructed of flexible sheet metal and secured upon the bottom rail of 25 the swinging sash and the sill of the window frame, respectively, one of said strip elements having a tubular part open at one side, said tubular part in cross section being 30 of general semi-circular shape, and the other strip element being provided with a vertically extending lower part and a hollow substantially semi-cylindrical roll at the upper end of said vertically extending lower part and 35 extending laterally to one side thereof, said semi-cylindrical roll being open at one side, and conforming to the size and shape of the 40

tubular part of the other strip element to fit within the same with its outer face throughout in close fitting engagement with the inner face of said tubular portion of the other strip element throughout the same when the swinging sash is in closed position. 45

3. The combination with a casement window or the like including a swinging sash, and a window frame having a sill, of a weather strip comprising two coöperating strip elements secured upon the bottom rail of the swinging sash and the sill of the window frame, respectively, one of said strip elements having a tubular part open at one side, and the other strip element being constructed from a strip of flexible sheet metal, 50 said strip being doubled upon itself intermediate its side marginal portions to provide a double wall flange with outstanding base flanges at opposite sides, the double wall flange having a lower flat part extending upwardly from its base, the two walls of said lower flat portion of the double wall 55 flange extending in contact, and said flange having a tubular portion at the upper end of and extending to one side of said lower flat upstanding part, said last mentioned tubular portion being open at one side, and 60 being of a size and shape corresponding to the interior of the tubular part of the other strip element to fit within the same with its outer face throughout in close fitting engagement with the inner face of said tubular part of the other strip element when the 65 swinging sash is in closed position. 70

In testimony whereof I hereunto affix my signature in the presence of two witnesses.

JOSEPH P. GLASER
